UNITED STATES PATENT OFFICE.

GUSTAF HAGLUND, OF FALUN, SWEDEN.

AUTOMATICALLY-ACTING LIXIVIATION APPARATUS.

Application filed February 16, 1922. Serial No. 537,104.

To all whom it may concern:

Be it known that I, GUSTAF HAGLUND, citizen of Sweden, residing at Falun, Sweden, have invented certain new and useful Improvements in Automatically-Acting Lixivation Apparatus, of which the following is a specification.

The object of the present invention is to provide an automatically operating lixiviation apparatus, especially for ores. The same consists of a plurality of coating horizontally located rotary cylinders or drums, each of which is equipped with a feed opening and a transport device for carrying the material to be lixiviated in a certain direction as well as a further transport device for carrying the liquid in the opposite direction.

The essential features of the invention are, that both transport devices are located at the end of the drum lying remote or opposite to the feed opening and that they consist of two spiral elevators, the one of which catches lixiviation material mixed with liquid from the interior of the drum and transports this mass up to a conduit or the like, which is situated in the central part of the apparatus and opens outwardly, and serves for removing the treated mass, whereas the other transport device receives fluid from the outside and transports the same to another centrally arranged conduit, which has a lesser diameter than the first named conduit and opens inwardly, so as to lead the fluid into the drum.

Preferably the inlet opening in the spiral elevator for the lixiviation mass is equipped with a valve, by means of which the feed velocity of the mass may be controlled automatically.

A constructional form for the invention is shown in the accompanying drawings, in which:

Figure 1 shows a section through an apparatus in accordance with the invention.

Figure 2 is a section on the line I—I of Figure 1.

Figure 3 is a section on the line II—II of Figure 1.

Figure 4 is a front view of an automatic valve device arranged on the spiral elevator for the lixiviation mass.

Figure 5 is a section through the same device.

1 denotes the feed opening and 2 the lixiviation drum, which by means of the rings 3 may be rotated through suitable roller devices. In the end of the drum remote to the feed opening a cylindrical part 4 is arranged, which has the same diameter as the drum. This part is formed as a spiral elevator, which carries the lixiviation mass in the lower part of the drum, as well as such fluid as might be at hand in this place, up through the spiral 9 and through the opening 10 into the conduit 7, from which the mass is decanted into the next drum.

To the spiral elevator 4 and concentrically with the same a cylindrical part 5 is fixed, which also is formed as a spiral elevator. The latter is preferably of a lesser diameter but of a greater width than the part 4. To the spiral elevator 5 a cylinder is fastened which is of the same diameter but preferably of a lesser width than the elevator. The outwardly pointing opening of this cylinder has inturned edges. The said cylinder is so dimensioned that the feed opening of the next drum may pass into the same and has a sufficient play.

In this cylinder the fluid is collected, which is decanted from the previous drum, and is transmitted to the spiral elevator 5, which by means of the spiral 11 carries the solution through the opening 12 in the conduit 7 to the inner conduit 8, from which the fluid is emptied into the first drum.

The automatic valve device which, if desired, may be mounted upon the apparatus, is shown on the Figures 4 and 5. The spiral elevator 4 is as will be seen on the said figures, equipped with a valve disc 15. This has an inner guide 14, which in the shown example projects over substantially the half height of the spiral opening. The disc 15 has an opening, which is of the same size as the opening between the guide 14 and the wall of the elevator. 16 is an outer guide for the valve disc. This guide is preferably equipped with packings to prevent leakage around the disc 15. 17 is a preferably adjustable spring device, which presses the disc outward, so that the opening in the elevator

is kept fully closed or fully or partly open. 18 is an arc shaped control rail for the valve.

The intermediate spaces between the spiral canals in the elevators are filled with 5 an acid-resisting material in order to stabilize the spirals. The material in these and in all other parts coming into contact with the liquid must of course also be built up from resistive material or coated with such.

10 The apparatus operates in the following manner:

Assuming that a plurality of drums are arranged as shown in Figure 1 and rotated, the mass which is fed into the first drum, 15 and which is to be lixiviated under continuous mixing with the liquid, will follow the bottom of the drum and together with the fluid be caught by the spiral elevator 4, by which the mass through the conduit 7 is 20 conducted into the next attached drum. In this the mass will meet a more diluted fluid or solution, which will lixiviate the material and dilute the fluid accompanying the same. The arrows shown in full lines in the drawing indicate the way which the material and 25 the fluid will follow. The diluted solution which is coming from the attached drum will follow the way indicated with dotted arrows, from the cylinder 6 through the spiral elevator 5 it is conducted up into the conduit 8, the bottom of which is situated higher than 30 the bottom of the feed opening. From the conduit 8 the solution flows into the drum, where it is mixed with the mass, which thereby is lixiviated and with the liquid at hand, which is diluted, whereupon the said solution 35 flows out through the feed opening and eventually into a further drum.

The manner of operation of the automatic 40 valve is as follows:

Over the greater part of a revolution the valve disc is pressed outward by means of the spring 17, whereby the opening in the elevator is kept closed. When however, the 45 valve is passing over the controlling rail 18 the disc will on account of the form of the rail be pressed inward and at a predetermined point produce a full opening in the elevator. By means of this arrangement it 50 is possible to keep the inlet opening of the elevator automatically closed when the elevator passes through the fluid in the drum and to automatically open the inlet opening when the elevator is passing through the 55 lixiviation mass proper.

Thus the filling of the elevator with liquid before it submerges into the material to be lixiviated, is avoided and the said material is fully or partly prevented from entering 60 the elevator. It is thus evident that the efficiency of the apparatus is increased considerably by means of the valve arrangement.

As will be understood it is possible to couple together as many drums as desired,

which may operate in series. The material 65 to be lixiviated is fed continually into the first drum, passes automatically through the entire arrangement and leaves the last drum in completely prepared state. Diluted solutions and such which do not have a sufficient grade of concentration, are conducted 70 into the last drum and leave the first drum in a saturated state.

All drums are arranged on the same level.

The feeding may be increased by increasing 75 the velocity of rotation. Further the feeding and the rotation may be adjusted, in accordance with the nature of the material. If desired also additional amounts of liquid 80 may be introduced into each drum separately.

If necessary heating elements may be arranged in the part of the apparatus through 85 which the liquid is let in, so that the same may be heated.

The constructional details of the arrangement may of course be varied in several ways without departing from the spirit of the invention.

Having now particularly described and ascertained the nature of my said invention and in what manner the same is to be performed, I declare that what I claim is:

1. Automatically operating lixiviation apparatus consisting of a plurality of coating 95 horizontally disposed rotary drums each of which is provided with a feed opening, a transport device associated with each drum for carrying material to be lixiviated in a certain direction, another transport device 100 associated with each drum for carrying the liquid in an opposite direction, both transport devices being located at the end of the drum opposite the feed opening and consisting of two spiral elevators, one of the transport devices receiving lixiviation material 105 mixed with liquid from the interior of the drum, a conduit situated in the central part of the apparatus to which the said mass is transported and the conduit opening outwardly and serving to remove the treated mass, the other transport device receiving fluid from the outside, another centrally arranged conduit receiving fluid from the second mentioned transport device and having 110 a smaller diameter than the first mentioned conduit and opening inwardly so as to return the fluid to the drum.

2. Lixiviation apparatus as claimed in 115 claim 1 wherein an acid-resisting material is arranged in the intermediate space between the spiral canals of the elevator in order to stabilize the same.

3. Lixiviation apparatus as claimed in 120 claim 1 wherein a valve is mounted at the inlet opening of the spiral elevator for automatically regulating the feeding of the material.

4. Lixiviation apparatus as claimed in substantially as and for the purposes set forth.
claim 1 wherein a spring-actuated valve is arranged through the wall of the drum and located at the inlet opening of the spiral elevator and a control device located outside the drum for completely or partly closing the inlet opening of the spiral elevator during a part of the revolution of the drum,

In testimony whereof I affix my signature in presence of two witnesses.

GUSTAF HAGLUND.
